UNITED STATES PATENT OFFICE.

EUGENE R. DURKEE, OF BROOKLYN, NEW YORK.

DESIGN FOR BOTTLES.

Specification forming part of Design No. 7,181, dated February 17, 1874; application filed December 19, 1873.
[Term of Patent 14 years.]

To all whom it may concern:

Be it known that I, EUGENE R. DURKEE, of Brooklyn, Kings county and State of New York, have invented a Design for Sance, Cologne, and other Bottles, of which the following is a specification:

The nature of the design is fully represented in the accompanying drawing, to which reference is made, the same letters of reference, wherever they occur, referring to like parts.

A represents the body of the bottle, and B the neck thereof, which is intended to be made of glass, either colored, opaque, or of its natural color, as may be desired, or may be made of porcelain or other suitable earthenware adapted for such purposes, and easily and cheaply made. The shape of the body of the bottle is hexagonal, tapering from about its middle lengthwise to the neck, where it terminates in a round, for about two and a half inches, more or less, below the mouth of the bottle. From the junction of the converging sides of the bottle with the rounded part of the neck down to the bottom of the bottle are formed a series of annular corrugations, C, with intermediate or alternating blanking spaces D, formed by the sides of the bottle. On the lower half of the bottle these corrugations are of uniform diameter; but for the upper half, where they terminate at the round of the neck, they are gradually diminished in diameter, to harmonize with the diminishing area of the bottle at that point. At the point E one of the faces of the bottle is left blank, with a lance-pointed top, for the purpose of forming a tablet for the pasting thereon of a label. This tablet, however, is not an essential feature of the design, nor necessary for

the pasting of a label on the bottle, as it may be omitted entirely, and the label pasted upon the corrugations. As a general rule, it is proposed making the bottle with the tablet; but as others may deem the omission of the tablet from the design an evasion of the invention, I therefore desire it to be included in my design for ornamenting bottles, that the essential feature of the design consists in alternating a series of corrugations and blanking spaces throughout the length of the bottle, either with or without the tablet.

It will be obvious the design of forming corrugations alternating with blank spaces throughout the length of the bottle is not dependent upon a hexagonal bottle, but may be applied to round, or square, or any other many-sided bottle with equally aesthetic results. I therefore desire it to be understood that the design is intended to include any and all bottles of the longitudinal configuration of cologne-water or champagne bottles, whether made of glass or other material.

Having now described my invention of a design for ornamenting the sides of bottles, I will proceed to set forth what I claim and desire to secure by Letters Patent of the United States.

What I claim as my invention is—

The series of corrugations and intervening or alternating blanking spaces encircling the body of the bottle throughout its length, substantially in the manner above described.

EUGENE R. DURKEE.
